UNITED STATES PATENT OFFICE

2,091,152

OSCILLOGRAPH

José T. Mireles Malpica, Schenectady, N. Y., assignor to General Electric Company, a corporation of New York

Application June 17, 1936, Serial No. 85,812

12 Claims. (Cl. 234—61)

My invention relates to recording apparatus and concerns particularly oscillographs of the type employing a deflectible beam of radiant energy to produce the record curve.

5 The principal object of my invention is to provide an arrangement for producing with a cathode ray oscillograph clearly-visible and well-defined permanent record curves of very rapidly varying phenomena, particularly phenomena 10 which are very short in duration and nonrecurrent.

It is an object of my invention to provide an arrangement for causing the deflections traced on a fluorescent screen to record directly upon a 15 sensitive film instead of being photographed.

It is an object of my invention to provide a light concentrator for sensitive film oscillographs.

It is also an object of my invention to arrange a cathode ray oscillograph to make relatively long 20 records.

Other and further objects and advantages will become apparent as the description proceeds.

For the observation of extremely high-speed phenomena, cathode ray oscilloscopes are known 25 in which a beam of radiant energy, impinging on a fluorescent screen to make the end of the beam visible, is electrostatically or electromagnetically deflected along transverse axes to trace a curve on the fluorescent screen, which, by 30 persistence of vision, appears to the eye as a continuous curve. In the case of regular wave forms of alternating quantities or in the case of regularly recurring transients, a record of the phenomena may be made by photographing the 35 curve traced on the fluorescent screen as in photographing any object. However, in the case of isolated transients, which cause the beam to trace the curve on the screen only once, insufficient light is produced for photography. In carrying out my invention in its preferred form, I 40 do not photograph the fluorescent screen with a camera in the ordinary way but I cause the light spots on the screen to affect the photographic film directly by passing the film as close as possible to the fluorescent screen in order to increase the effect upon the film. In order to prevent either blurring of the film or complete loss of the image by diffusion of the light from the light spots, I may provide a suitable condenser or light 45 concentrator between the wall of the cathode ray tube and the photographic film.

The invention will be understood more readily from the following detailed description when considered in connection with the accompanying 50 drawings and those features of the invention

which are believed to be novel and patentable will be pointed out in the claims appended hereto. In the drawings, Fig. 1 is an end elevation, partially in section, of a film-driving mechanism for a cathode ray oscillograph embodying my invention, the cathode ray tube and a portion of the film being removed to present a view into the film-driving mechanism; Fig. 2 is a side elevation, partially in section, of the mechanism of Fig. 1, together with the end portion of a cathode ray tube with a light-concentrating shield; Fig. 3 is a schematic diagram showing the beam deflection in a cathode ray oscillograph; Fig. 4 is a fragmentary enlarged sectional view of a portion of the apparatus of Fig. 2 showing a section cut by a plane extending lengthwise through the light-concentrating shield perpendicular to the plane of the paper in Fig. 2; Fig. 5 is an enlargement of a portion of Fig. 2 showing a section of the part of the light shield immediately 20 surrounding the light concentrator; Fig. 6 represents a modification of the apparatus of Fig. 5; Fig. 7 is a graph illustrating a form of curve which may be produced with the apparatus; Fig. 8 is a diagram showing a portion of the glass wall 25 of a cathode ray tube and a fluorescent screen and explaining the diffusion of light from a point on the screen; Fig. 9 is another diagram showing graphically the diffusion and variation in strength of light emanating from a bright spot 30 on the screen; Fig. 10 is a graph illustrating the effect of diffusion in tracing a sine wave; Fig. 11 is a fragmentary sectional view (corresponding to Fig. 5) of a light shield with the openings filled by quartz rods, the section cutting plane 35 being parallel with the direction of travel of the film as in Figs. 2, 5, and 6; Fig. 12 is a fragmentary sectional view of a modified arrangement with lenses embedded in the end wall of a cathode ray tube, the section cutting plane being perpendicular to the direction of travel of the film as in Fig. 4; Fig. 13 is a fragmentary sectional view of a modified arrangement with quartz tubes 40 inserted in the end wall of the cathode ray tube, the section cutting plane being perpendicular to the direction of travel of the film as in Figs. 4 and 12; Fig. 14 is a fragmentary view of a modified light shield, looking toward the end of the cathode ray tube, for use with stationary instead of moving films; Fig. 15 is a modification of the arrangement of Fig. 16 with a fabricated structure and Fig. 16 is a sectional view of a modified construction having a light shield integral with the end wall of a tube. Like reference charac- 45

ters are utilized in the drawings to designate like parts throughout.

As is well known, cathode ray oscilloscope tubes are provided with suitable arrangements for generating the rays and focusing them to form a narrow beam. Since my invention does not relate to these arrangements, they need not be illustrated or described. As illustrated in Fig. 3, such a tube 11 is provided with suitable means, such as an electromagnetic coil or a pair of electrostatic deflection plates 12, for deflecting a beam between two limits, such as 13 and 14. The end wall 15, which is usually circular, is made convex and lined with a fluorescent screen 16 which produces a momentary spot of light at the points where the cathode rays impinge. The deflection plates 12 alone deflect the beam within a plane parallel to the paper and substantially intersecting the tube 11 in accordance with variations in a voltage to be measured which is applied between the plates 12. For providing a timing axis and deflecting beam transversely, a second pair of deflecting plates 17 may be provided in oscilloscopes in which a curve traced on the fluorescent screen 16 is to be viewed directly by the human eye. When the phenomenon observed is recurrent and retraces the same curve indefinitely, a record thereof may be obtained by photographing it since, by continued exposure of the photographic film to the curve, enough light may be obtained to affect the film.

However, in accordance with my invention, since I desire to obtain records of nonrecurrent phenomena, the momentary traces of which on the fluorescent screen cannot ordinarily be successfully photographed, I place a sensitized chart or film 18 against the end wall 15 having the fluorescent screen 16. Instead of employing the deflection plates 17 to obtain a timing axis for the curve, I cause the film 18, itself, to be moved in a direction perpendicular to the plane of the paper in Figs. 3 and 4 and I permit the cathode ray beam to deflect only in a single plane under the influence of the deflection plates 12.

In order to avoid fogging the film, I provide a shield 19 covering the entire end 15 of the tube 11, except for openings in the plane of deflection 13-14 of the cathode ray beam. For the sake of avoiding blurring or dimming of the record curve by diffusion of the light from the fluorescent screen 16, I provide a light concentrator in the form of a row of perforations 20 in the shield 19. The perforations 20 have their axes perpendicular to the surfaces of the fluorescent screen 16, the tube end wall 15, and the shield 19, and all the axes lie within the plane of deflection 13-14 of the cathode ray beam. If desired, an insert 21, shown enlarged in transverse section in Fig. 5, may be provided in the shield 19 for carrying the openings 20. The insert 21 is of opaque material, the surfaces of the perforations 20 are blackened, and preferably the inner surface of the shield 19 is also blackened to minimize stray light.

Since the shield 19 is provided with a row of perforations rather than a continuous slit for the passage of the light rays affecting the sensitive film 18, any curve produced by the oscilloscope will appear as a series of dots as illustrated in Fig. 7. This circumstance permits me to provide a convenient way for providing scale divisions on a plain film as the record is being produced. The perforations 20 are properly spaced to product unit graduations and every tenth perforation is of greater diameter to produce larger light spots 22, representing graduations in mul-

tiples of ten. Furthermore, the small perforations on either side of the larger perforations are omitted to define a zero line through the larger light spots 22 separated from the rest of the curve by short gaps on either side of the zero line. If desired, either the light spots 22 or 23 may also be made distinguishable by employing openings of a different shape or character.

Any suitable means may be provided for causing the sensitive film 18 to pass along the light-concentrating shield 19. For example, the film may be carried by two spools 24 and 25 (Figs. 1 and 2), being wound upon the spool 24 and unwound from the spool 25 by the motor 26, driving the spool 24 through suitable gearing 27. The spools 24 and 25 are suitably journaled within a lightproof box 28 wholly surrounding the end portion of the cathode ray tube 11. A strip spring 29 may be provided for keeping the film 18 compactly rolled on the spools 24 and 25.

The accumulation of static charges by the film 18 is prevented by providing a metallic shield 30 electrically connected to the metallic housing 28. A felt cushion 31 and phosphor bronze springs 32 serve to hold the film 18 closely but resiliently against the light-concentrating shield 19 over the perforation 20.

Fig. 8, showing in section, greatly enlarged, a portion of the tube end wall 15 and the fluorescent screen 16, illustrates the effect of the glass wall 15 in causing diffusion of the light emitted from a single point 33 on the surface of the fluorescent screen 16 where the light has been generated by a cathode ray impinging upon the screen 16. Owing to refraction of the light rays upon emergence from the glass wall 15, still greater diffusion takes place outside the wall 15 of the tube. In actual practice, the deflecting beam of the cathode ray tube consists of a bundle of cathode rays producing a light spot 34 of finite area on the fluorescent screen 16 (Fig. 9), and the area of this light spot becomes considerably enlarged upon emergence from the glass wall 15.

The curve 35 represents by its distance from the outer surface 36 of the wall 15 the relative intensity of light at various points on the surface 36. At the surface 36, the light spot becomes progressively dimmer toward the edges, owing to greater deviation from normal of the light rays. In consequence, although a cathode ray beam may actually follow a sharp curve, such as the curve 37 (Fig. 10), a light-sensitive film placed against the surface 36 (Fig. 9) would have a broadly and dimly illuminated band 38, becoming dimmer toward the edges, so that the record curve actually recorded would be both indistinct and lacking definiteness of position. Such disadvantages are overcome, however, by the interposition of my light-concentrating shield 19. Since the perforations 20 are all perpendicular or normal to the fluorescent screen 16 and the perforations are of appreciable length relative to their diameters, only the relatively powerful normally energizing rays are permitted to strike the film 18 and a distinct definite curve is produced as illustrated in Fig. 7. The perforations 20 provide light paths perpendicular to the screen 16 and so transmit only effective light rays perpendicular to the screen 16 and the end wall of the tube.

For the sake of illustration, I have described my invention in connection with cathode ray tubes producing electron emissions impinging upon a fluorescent screen to generate light and other rays, such as actinic rays, to which a photographic type of film is sensitive. It will be under-

stood, however, that my invention is not limited to this precise arrangement and obviously includes tubes producing other types of radiant energy than cathode rays as well as such tubes or other types of oscillographs in which no fluorescent screen is used and the radiation falls directly upon a suitable sensitive chart or film.

I have also obtained successful records employing a relatively thin perforated shield but 10 obviously greater curve sharpness is obtainable with the relatively thick shield 19 since any danger of divergent light rays passing through the shield is eliminated. As an alternative to the arrangement hereinbefore described and illustrated in detail in Fig. 5, under certain circumstances in order to obtain increased brilliancy, I may employ a light shield having a row of conical openings 39 (as illustrated in Fig. 6) with polished internal walls, the smaller diameter 20 ends 40 of the openings being toward the film. Such openings serve as reflecting condensers, being substantially equivalent to very deep parabolic mirrors with their apices cut off.

If desired, cylindrical rods of quartz 41 or 25 other material having a high transmission and suitable index of refraction may be fitted into the openings 20 of the arrangement of Figs. 2, 4, and 5 to serve as light condensers as illustrated in Fig. 11. The rods 41 may be inserted directly 30 in the shield 19 instead of employing the insert 21. Condensing lenses 42 might, of course, also be employed, preferably embedded in the surface of the glass wall 15 as illustrated in Fig. 12. By embedding the quartz rods 41 in the glass wall 35 15, as shown in Fig. 13, a direct non-diffusing path would be provided for the light rays emanating from the fluorescent screen 16.

In case the oscillograph is to be operated with a stationary sensitive film and the timing and 40 measuring axes are obtained by deflecting the beam along transverse paths, the entire working portion of the shield 19 is provided with perforations 20 or with some other form of light transmitting paths perpendicular to its surface. To 45 permit putting the perforations as close together as possible, they may be staggered with centers at the intersection of 60-degree lines as shown in Fig. 14, which represents a fragment of an end view of a modified form of shield 19.

50 If desired the effective spacing between the light transmitting paths in the shield 19' may be decreased by utilizing hexagonal openings or hexagonal-prism light transmitters placed immediately adjacent as illustrated in Fig. 15. Fig. 55 15 is a fragmentary end view of the shield 19' magnified to show more in detail that light transmitting openings 42 are formed by joining opaque sheet material to produce hexagonal-prism-shaped spaces. Such spaces may, if desired, be 60 filled with a suitable light transmitting substance such as a transparent resin which may be melted and poured into the openings and then allowed to cool and harden. A suitable backing plate will, of course, be temporarily used to prevent the 65 liquid from running out of the openings.

Among the resins which may be used for this purpose are a synthetic resin manufactured by Rohm & Haas Co., Inc., under the trade name "Plexiglass" and a resin manufactured by the 70 Du Pont de Nemours Co. under the trade name "Pontalite", which I believe to be polymeric esters, largely polymethyl methacrylate. In using such material the liquid monomer, methyl methacrylate may be poured into the openings 42 75 and then polymerized and solidified by heat. I

understand methyl methacrylate to have this formula:

5

In case the openings 42 are filled, the shield 19' may form a part of the end wall 15 of the tube 11 and the fluorescent screen 16 may form a coating on the back of the shield 19'. It will 10 be understood that the shield will be suitably sealed to the remainder of the tube 11 to form an air-tight envelope as illustrated in Fig. 16.

Instead of filling up the openings in a grid such as shown in Fig. 15, the light shield may be 15 made up by cementing together hexagonal prisms of glass, quartz, transparent resin or other suitable substance to produce a formation such as that appearing in Fig. 15. The side surfaces of the prisms may be sandblasted, etched or 20 otherwise made opaque or an opaque cement may be employed for joining the prisms.

For slow-speed oscillography, the fluorescent screen may be composed of zink silicate but, for high-speed work in order to avoid leaving a 25 blur on the rapidly traveling film, I prefer to use a material such as calcium tungstate which is fast acting and does not leave an afterglow.

I have herein shown and particularly described 30 certain embodiments of my invention and certain methods of operation embraced therein for the purpose of explaining its principle and showing its application but it will be obvious to those skilled in the art that many modifications and variations are possible and I aim, therefore, to 35 cover all such modifications and variations as fall within the scope of my invention which is defined in the appended claims.

What I claim as new and desire to secure by Letters Patent of the United States, is:

40 1. A cathode ray oscillograph comprising an evacuated envelope with a fluorescent screen on a wall of said envelope, means for deflecting a cathode ray along a path across said screen in accordance with variations in a measured quantity, a sensitized chart, means for passing said chart along said fluorescent screen transverse to the path of deflection of the cathode ray, a relatively thick opaque shield interposed between said fluorescent screen and said chart with a row 45 of openings each perpendicular to said screen, and in the path of the cathode ray, and means for shielding said chart from any actinic rays except such as pass through said openings in said shield.

50 2. An oscillograph comprising in combination, a fluorescent screen, means for deflecting a beam of radiant energy across said screen in accordance with variations in a measured quantity, a sensitized chart, means for passing said chart along said fluorescent screen, and a relatively thick opaque shield interposed between said fluorescent screen and said chart with a row 55 of openings, each perpendicular to said screen.

3. An oscillograph comprising in combination, a fluorescent screen, means for deflecting a beam of radiant energy across said screen, a sensitized chart, means for passing said chart along said fluorescent screen, and an opaque shield interposed between said fluorescent screen and said chart, said screen having a row of openings in the line of motion of said beam.

4. An oscillograph comprising in combination, means for producing a beam of radiant energy, means for deflecting said beam substantially in 75

a plane, a sensitized chart having a surface transverse to said plane, means for moving said chart parallel to itself in a direction transverse to said plane, and an opaque shield adjacent said chart interposed between said chart and said beam-producing means, said shield having a row of openings therein with centers in the plane of deflection of said beam.

5. An oscillograph comprising in combination, 10 means for producing a beam of radiant energy, means for deflecting said beam substantially in a plane, a sensitized chart having a surface transverse to said plane, means for moving said chart parallel to itself in a direction transverse to said 15 plane, and an opaque shield adjacent said chart interposed between said chart and said beam-producing means, said shield having a row of openings therein with centers in the plane of deflection of said beam, said openings being placed 20 at uniform spacings, and including openings differentiated from the remaining openings and spaced at multiples of the spacings of the remaining openings.

6. An oscillograph comprising in combination, 25 a fluorescent screen, means for deflecting a beam of radiant energy across said screen in accordance with variations in a measured quantity, a sensitized chart, means for passing said chart along said fluorescent screen, and a relatively 30 thick opaque shield interposed between said fluorescent screen and said chart with a row of openings each perpendicular to said screen, said openings being conical with their smaller diameters toward said chart and having their interiors polished.

7. An oscillograph comprising in combination, 35 a fluorescent screen, means for deflecting a beam of radiant energy across said screen in accordance with variations in a measured quantity, a sensitized chart adjacent said screen and a relatively thick shield interposed between said fluorescent screen and said chart with a plurality of openings therein perpendicular to said screen.

8. An oscillograph comprising in combination,

a fluorescent screen, means for deflecting a beam of radiant energy across said screen in accordance with variations in a measured quantity, a sensitized chart adjacent said screen and a relatively thick shield interposed between said fluorescent screen and said chart with a plurality of relatively small rectilinear light transmitting paths perpendicular to said screen.

9. An oscillograph comprising in combination 1 a fluorescent screen, means for deflecting a beam 1 of radiant energy across said screen in accordance with variations in a measured quantity, a sensitized chart adjacent said screen, and a member interposed between said fluorescent screen and said chart with a plurality of light 1 transmitting paths having boundaries for diverting light rays not perpendicular to said screen.

10. An oscillograph comprising in combination 2 a fluorescent screen, means for deflecting a beam 2 of radiant energy across said screen in accordance with variations in a measured quantity, a sensitized chart adjacent said screen, and a member interposed between said fluorescent screen and said chart with a plurality of light-concentrating devices providing light transmitting paths perpendicular to said screen.

11. An oscillograph comprising in combination a fluorescent screen, means for deflecting a beam of radiant energy across said screen in accordance with variations in a measured quantity, a sensitized chart adjacent said screen, and a member interposed between said fluorescent screen and said chart with a plurality of quartz rods therein perpendicular to said screen.

12. In a radiant-energy-beam oscillograph, means for producing a radiant-energy-beam deflectable within a plane, and a light-concentrating shield for the oscillograph comprising an opaque plate adapted to cover the beam-receiving end of the oscillograph and having a row of openings therein with axes within said plane and perpendicular to said plate.

JOSÉ T. MIRELES MALPICA.
